UNITED STATES PATENT OFFICE.

GEORGE H. DAY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

LENS-FRAME.

1,273,830.

Specification of Letters Patent. Patented July 30, 1918.

Application filed December 26, 1917. Serial No. 208,940.

To all whom it may concern:

Be it known that I, GEORGE H. DAY, a citizen of the United States, residing at Southbridge, in the county of Worcester 5 and State of Massachusetts, have invented certain new and useful Improvements in Lens-Frames, of which the following is a specification.

This invention relates to new and useful 10 improvements in goggles and more particularly to the lens holding frame therefor and is a division of my application filed June 8, 1916, Serial No. 102,450 the main object of this invention being the provision of a lens 15 frame so constructed whereby the same is reinforced at its longitudinal edges to prevent it from becoming bent or distorted.

Another object of the invention is the provision of a lens frame for goggles wherein 20 the same is constructed so that a screen member can be quickly and readily attached thereto and is mounted for a free swinging movement, but at the same time fitted tightly against the frame when in an open or operating position.

A further object of the invention is the provision of a lens frame for goggles wherein 25 the same is provided with a reinforced portion which not only tends to brace the frame to assist in retaining the lens in place but serves as a substantially smooth engaging surface for the face when the goggles are applied thereto.

With the above and other objects in view 30 the invention consists in the novel features of construction and the combination and arrangement of parts hereinafter more fully set forth, pointed out in the claims and shown in the accompanying drawings, in 35 which:

Figure I is a front elevation of a pair of goggles including frames constructed in accordance with my invention.

Fig. II is a side elevation of the frame in 40 a flattened or unfolded position.

Fig. III is a detail perspective of a portion of the frame showing a transverse section through the same.

Fig. IV is a transverse sectional view 45 taken through one end of the frame, showing the same slightly rolled at one edge and the lens in position.

Fig. V is a detail side elevation showing

a covering as applied to that part of the frame which contacts with the face; and 55

Fig. VI is a detail perspective view of a portion of the frame looking toward the exterior thereof.

In the accompanying drawings forming a 60 part of this application it will be noted that in Fig. I, I have illustrated a pair of goggles showing the application of my improved frame and in the construction of these goggles the numeral 1 indicates the nose bridge which connects the two lens frames 2 which are further held in place by the supplemental or bracing bridge connecting the lens frames 65 at a point adjacent the top thereof.

These frames are provided with the usual 70 temples 4 whereby the goggles may be readily applied to the face of the wearer.

In the construction of these lens frames an elongated blank of metal is used, having its central portion provided with an arcuate extension 6 located at substantially midway 75 of its ends whereby the frames will be fitted closer to the face at a point adjacent the nose of the wearer. At one edge of the blank 5 the substantially V-shaped groove 7 is formed for the reception of the lens 8 which 80 is held in place by the fastening of the two ends of the frame. The opposite edge of the blank is provided at each end of the blank with a reinforced beading 9 formed by doubling the edge of the blank upon itself 85 and folding the edge down tightly onto the blank to provide a substantially flat beading, this beading extending from each end of the blank inwardly to a point at each end of the arcuate extension 6 and the edge of 90 the blank extending around the arcuate extension is curled or rounded upon itself as shown at 10 to provide a relatively hollow beading the ends of which connect with the inner ends of the flat beading 9. It will be 95 apparent from the illustration in Fig. III that a screen member may be readily attached to each of the frame members and when disposed in an open position fit tightly against the beading to prevent any dust or 100 other particles from passing between the screen and frame.

It is to be understood that the frame members 2 are preferably provided with suitable end pieces 11 to detachably unite their 105 ends whereby the lenses 8 are locked into

position by the tightening together of these end pieces. In providing for a fastening device to secure the goggles to the face the temples 4 are attached to the end pieces 11 although it will be fully understood that any suitable fastening means may be attached to these end pieces in place of the temples herein shown.

In Fig. V I have illustrated the frame as provided with a covering 13 which is applied to the hollowing beading 10 to provide a soft yieldable contacting surface for the face to prevent the face of the wearer from becoming bruised should an object come in contact with the outer edges of the frames. This covering is preferably made as detachable so that the goggles can be used either with or without this cover. From the above description taken in connection with the accompanying drawings it will be apparent that I have provided a frame for goggles which is solid in its construction and is so reinforced as to prevent the same from becoming easily bent or distorted and at the same time this reinforcement will tend to assist in holding the lens in place within the groove 7 by preventing the spreading or bending of the frame.

I claim:

30 1. A frame of the class described includ-

ing an elongated blank having a lens receiving groove in one edge thereof, a beading extending the entire length of the blank at the other edge, the central portion of said beading being rounded in form and the end portions being substantially flat.

2. A frame of the class described including an elongated blank having a lens receiving groove in one edge thereof, an arcuate portion at the intermediate portion of the frame, the edge of said arcuate portion being curved into a round beading, and the ends of the frame having a flat beading extending from each end of the round beading to each end of the frame.

3. A frame member for an eye protector or the like, comprising a strip of material having a lens engaging groove at one edge thereof, the other edge of said strip being bent upon itself to form a reinforcing bead, the central portion of which is rounded and slightly curved and its ends flattened and disposed substantially parallel with the lens groove.

In testimony whereof I have affixed my signature in presence of two witnesses.

GEORGE H. DAY.

Witnesses:

Wm. P. CHASE,
WILLIAM B. JONES.
